SPRAYER

Andrew Madsen, Stillwater, Minn.

Application October 31, 1932, Serial No. 640,489

2 Claims. (Cl. 299—89)

My invention relates to improvements in spray-
ers of the class used for spraying foliage or ex-
terminating bugs, fleas and other kinds of in-
sects.

5 The main object of this invention is to pro-
vide a continuous or uniformly atomized exhaust
from such sprayers by means of certain con-
struction of nozzles and feed means thereto and
as hereinafter fully set forth, reference being had
10 to the accompanying drawing, in which,—

Fig. 1 is a longitudinal sectional elevation of a
hand operated sprayer of well known type and
embodiment my improvements.

Fig. 2 is an enlarged sectional view as on line
15 2—2 in Fig. 1 showing my nozzle means and liquid
feed means thereto more fully, and the tapered
forward part of the sprayer indicated in dotted
lines only.

Figs. 3 and 4 are respectively cross sectional de-
20 tail views at lines 3—3 and 4—4 of Fig. 1, showing
certain details of a diametrically mounted tube
11 in the reservoir 10 of the sprayer and com-
prising an important feature of my invention.

Referring to the drawing by reference numer-
25 als, I have illustrated my improvements as em-
bodied in one of the well known type of hand
operated sprayers comprising an elongated cylin-
der 5 tapered as 5T to its forward end. 6 is a
30 transverse wall at the junction of the straight
and tapered parts and in which is provided any
suitable type of check valve 7. 8 is the usual
piston reciprocable in the main cylinder by means
of the piston rod 9 to provide air pressure to be
35 exhausted from the small or nozzle end. 10 is a
cylindrical or can-like liquid reservoir suitably
fixed to the under side of the tapered or nozzle
end 5T of the sprayer. Communication is pro-
40 vided between the interior of the nozzle and the
interior of the reservoir only in the open upper
end of a central, fixed upright tube 11 extending
diametrically across the reservoir and its bottom
end closed or fixed to the inner surface of the
45 reservoir at 12 (Fig. 1).

13 designates a quantity of spraying liquid in
45 the reservoir and in which the tube 11 is of course
immersed. 14 are a number of seepage holes in
the lower part of tube 11 and through which
liquid may enter the tube until it reaches its
normal level. 15 are a pair of diametrically op-
50 posite vents in tube 11 near its upper end and
within the reservoir, said vents in transverse
alignment relative to the longitudinal center line
or direction of the compression cylinder 5 for
reasons presently to be set forth. 10F (Fig. 2) is
55 the usual filler cap for the reservoir.

It is well known, in the use of this type of
sprayer, they must be shaken considerably to
keep the contents of the reservoir at all times
thoroughly mixed and prevent settling of powders
mixed with the liquid. In doing this the liquid
splashes around within the reservoir usually in
a plane longitudinal of the device and in curva-
tures represented by arrows 16 (Fig. 1). For this
reason the holes or vents 15 are at right angles
10 to said splashing movement of the liquid to pre-
vent entry of any appreciable amount of such
liquid into tube 11 above the normal liquid level.
Now it is obvious that liquid 13 is completely in-
closed.

The nozzle end of the sprayer, designated N 15
as a whole in Figs. 1 and 2, is concentric with
the forward end of the tapered part 5T of the
main cylinder and located forward of the upper
end of the tube 11. 17 is a metal tube fixed in the
forward end part 5T and projecting forward 20
thereof the projecting part preferably provided
with (male) threads 17T (see Fig. 2).

Within tube 17 is retained concentrically a
liquid feed tube 18 projecting slightly forward
of the tube 17, said tube 18 extending rearwardly 25
and inwardly to the upper open end of the res-
ervoir tube 11, thence extending downwardly
within the latter tube, being preferably fixed to
the rear inner wall of the latter, and terminat-
ing with its lower end about centrally within tube 30
11 and spaced above the lower extremity of the
latter. Said latter end of the liquid conductor
tube is thus opening into the liquid in tube 11
and when air pressure is affected in part 5T
35 the compressed air forces the liquid in the tube
through tube 18 to the nozzle where it mixes
with compressed air passing forwardly between
the tubes 17 and 18. When the piston is retract-
ed some compressed air remains in part 5T which
40 air pressure continues to be expelled at the noz-
zle and also continues spray action of liquid as
described. Assuming that the sprayer piston is
reciprocated with fair speed and frequency it will
be readily understood that each forward stroke
45 is going into effect before the compression above
described is exhausted, thus providing continuous
and uniform spray from the nozzle. The pocket
20 is adjustable in size according to how far
the nozzle cap is threaded on, bringing the out-
50 let 19A of said cap to desired spaced relation to
tube 18 and thereby regulating the liquid and
air spray to any desired condition.

55 21 is a lock nut threaded on tube 17 inwardly
of the nozzle member or cap 19 and 22 is a suit-

- able washer between said two parts, to provide a leak-proof mounting of said nozzle parts.
- In the use of my device it will be readily understood that when compressed air is generated 5 within part 5T, some of it passes forwardly into the nozzle between the tubes 17 and 18 and some into the reservoir through the apertures 15 and pressing liquid into the tube 11 through the apertures 14 and thence into tube 18 to the nozzle.
- 10 Continuous or intermittent shaking of the sprayer as usually occurs during its use does not affect the spraying action. The intake end of tube 18 is submerged in a relatively constant and undisturbed quantity of the liquid within the tube 11.
- 15 The splashed main body of the liquid churns about within the reservoir 10 and does not have direct outlet to part 5T. Thus it is not possible for irregular feeding of liquid to the nozzle at any time with consequent irregularity of emitted 20 spray. In other words my liquid tube intake within tube 11 in an area undisturbed by splashing, provides for constant liquid spray at the nozzle, and too rapid or irregular spray is eliminated.
- 25 In the construction of my device various modifications may be made in structure and proportions of parts. In tube 11 the apertures 14 are small and provided in any suitable number and the apertures 15 may be relatively large and 30 preferably only two in number as stated. The lower end of tube 18 is located close to the bottom end of tube 11 mainly to insure drawing off of practically all of the liquid contents.

I claim:

- 35 1. In a sprayer comprising an air pressure pro-

ducing chamber and an air outlet nozzle communicating with said chamber, a liquid reservoir fixed to said outlet nozzle, said nozzle comprising a forwardly tapered chamber, a sprayer tube extending rigidly forward from said tapered chamber, a cap adjustable longitudinally on the front end part of said tube and provided with an outlet concentric of said tube; a fixed upright tube in said reservoir having its upper end in communication with the tapered chamber and 10 the lower end of said tube closed at the bottom of the reservoir, the walls of said tube provided with a number of apertures in proximity to the lower end, a liquid conveyor tube fixed within said upright tube with its lower end opening into 15 the lower central part of said tube, the upper part of said conveyor tube extending concentrically of and longitudinally through the first described sprayer tube and its forward end directed toward the outlet of the cap member but 20 spaced inwardly of the latter.

2. The structure specified in claim 1 in which 25 said upright tube in the reservoir is provided with a pair of comparatively large vent apertures in its upper part above the liquid level in the reservoir and in proximity to the tapered nozzle to provide passage means for air from the tapered nozzle into the reservoir above the liquid level, 30 said pair of apertures being diametrically opposite each other on a diametrical line transversely of the direction of the tapered nozzle for the purpose set forth.

ANDREW MADSEN.
